UNITED STATES PATENT OFFICE.

JOHN A. FERGUSON, OF DENVER, COLORADO.

MOLD FOR TILES.

1,244,845.

Specification of Letters Patent. Patented Oct. 30, 1917.

Application filed August 22, 1916. Serial No. 116,281.

To all whom it may concern:

Be it known that I, JOHN A. FERGUSON, a citizen of the United States, residing at Denver, in the county of Denver and State 5 of Colorado, have invented certain new and useful Improvements in Molds for Tiles, of which the following is a specification.

My invention relates to improvements in the manufacture of tiles from a suitable 10 plastic substance, and while it is particularly designed for making roofing tiles from a cementitious mixture, it will be understood that the word "tile" as herein used, is not limited necessarily to a roofing tile, but 15 includes analogous articles, wherein a similar element is laid in overlapped relation to another, as in tiling generally.

As such mixtures have a decided tendency 20 to settle, when in a fairly liquid state, I have found that, in making these more or less fragile articles, it is of great advantage to mold each tile facing downward in a settling pan.

The primary objects of this invention, 25 therefore, is to preserve the superior quality of such tiles as to uniform coherence and finished facing, and by providing a special series of mold elements, to produce a number of the tiles at substantially one operation, and in a novel manner with a minimum of time, labor and expense.

Other objects and advantages of the invention will hereinafter appear and the novel features thereof will be particularly 35 pointed out in the appended claim.

The invention is clearly illustrated in the accompanying drawings, which, with the numerals of reference marked thereon, form a part of this specification, and in which— 40 Figure 1 is a vertical longitudinal section through a plurality of pans with the tile or shingles molded and ready for removal.

Fig. 2 is a perspective view of one of the pans.

Fig. 3 is a perspective view of the under side of the bottom of the pan.

Fig. 4 is a perspective view of one of the completed tile or shingles.

Like numerals of reference indicate like 50 parts throughout the different views.

Referring to the drawings:

1 designates a pan of suitable material, preferably metal, the bottom of which upon its upper face is provided with one or more 55 transverse grooves 2 of any suitable contour, forming upon the under side thereof

the corresponding ridges 3, see Fig. 3. The bottom of the pan upon its upper face is formed with longitudinally extending grooves 4 forming upon the under side of 60 the bottom of the pan the corresponding ridges 5, see also Fig. 3. The side and end walls 6 of the pan are inseparably associated with its bottom, and preferably flare upwardly therefrom, as shown, to facilitate 65 removal of the molded article and one of these walls, in the present instance an end wall, is shown as provided with a slight edge recess 7, for a purpose which will hereinafter appear.

In some cases I may provide teats or the like 8 projecting upward from the bottom at one end, as seen in Fig. 2, for the purpose of producing nail holes in the molded article. These teats or projections may be tapered in some cases to provide tapered openings in the tile or shingles.

The surrounding marginal ledge 9 forms a rest or support for the pan, which pan is shallow, being substantially of a depth corresponding to the desired thickness of the 80 molded article.

In some instances I provide the pan with one or more inserts 10 at a corner or corners, which inserts may assume a shape corresponding to that desired to be given to the corner or corners of the molded article. In the present instance I have chosen to show them as beveled, see Fig. 2, to provide correspondingly beveled faces 11 at one end 90 of the tile, as shown in Fig. 4.

Having a plurality of pans substantially as above described, the tiles are molded as follows: A pan 1 is placed upon a suitable support. Plastic material 12 is then placed 95 in this pan and then another pan 1 filled with plastic material is superimposed thereon, and then another likewise filled placed on top of that, as seen in Fig. 1, and the same procedure followed until the requisite 100 number of pans are in position. The material is then allowed to set or harden sufficiently and then the completed articles are removed, first removing the uppermost pan with its tile, then the next pan with its tile, 105 and so on. The depressions 2 and 4 in the upper face of the bottom of the pan form beads or ridges on the adjacent face of the plastic material, while the ridges 3 and 5 on the under face of the bottom of the pan 110 form complementary grooves in the other face of the molded article, in true alinement

with said beads or ridges. The inserts 10 form at the corners of the completed article the beveled faces 11, as seen in Fig. 4. The teats 8 form corresponding nail holes 13 in the end of the completed tiles.

I may sometimes reinforce the tiles by means of a suitable reinforcement, as shown at 14 in Figs. 1 and 4, molded into the plastic material, as will be readily understood 19 upon reference to Fig. 1.

I may sometimes provide securing strips for the tiles, such as shown in Figs. 4 at 15, the said strips being molded into the tiles and provided in the present instance with 15 slots 16 of substantially keyhole shape to receive the securing means and to permit of ready removal of the tiles when necessary.

The securing strip 15 may be molded into either end of the tile. In some instances 20 it is useful at one end and in some instances at the other end. Both the nail holes and the securing strip may be present in the one tile or I may omit either as may be found most desirable.

25 Either or both ends of the pan may be provided with a recess 7 hereinbefore referred to to receive the securing strip 15 when the article is being molded. In some instances this securing strip is molded into 30 the end adjacent the inserts and in some instances at the other end. The pans are correspondingly provided with recesses 7.

The ridges and depressions of the completed molded articles are clearly seen in 35 Fig. 1. In Fig. 4 the longitudinal ridges 17 and the transverse ridges 18 are clearly illustrated.

Copies of this patent may be obtained for five cents each, by addressing the "Commissioner of Patents, Washington, D. C."

Minor modifications may be employed, in actual manufacture, without departing from the spirit of the invention, and it will be 40 understood that I contemplate such a range of equivalents as may fairly come within the scope of the ensuing claim, the essence of the invention residing primarily in the fact that I mold the tiles face downwardly, 45 with the top of the tile being formed, in molding, with transverse and longitudinal edge beads, and the bottom thereof with corresponding grooves, disposed in true complementary alinement with said beads. 50

Having thus described my invention, what I claim is:—

In molding apparatus for tiles substantially as set forth, a plurality of shallow mold pans, of uniform dimensions, each having a closed bottom, inseparable upwardly flaring end and side walls providing an unobstructed open top, and a laterally disposed external marginal flange support, the closed bottom being suitably depressed to 55 provide transverse and longitudinal pattern grooves along the inside face and congruent pattern beads on the outside face thereof, said grooves and beads being formed contiguous to but independently of their complementary end and side walls and disposed wholly within the bounded area of said open top, and the several elements functioning in 60 operation, substantially as described. 65

In testimony whereof I affix my signature 70 in the presence of a witness.

JOHN A. FERGUSON.

Witness:

J. E. GILES.
